UNITED STATES PATENT OFFICE.

DONALD G. MACKENZIE, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

STRIP DIAPER.

Application filed May 24, 1927. Serial No. 193,840.

Objects of the invention are to provide a comparatively inexpensive single use diaper constructed in such wise as to be non-irritating and generally non-discomforting, highly efficient, and capable of facile disposal; to provide a diaper of comparatively light weight and small bulk and yet possessed of maximum absorbent power; to provide a diaper having a duplex filling whereof one element is floated and readily conformable or adaptable and whereof the other element ranges crosswise beyond the limits of the first and is marginally secured to the casing or envelope; to provide a diaper casing whereof the portion which comes in contact with the person is highly porous and absorbent and exceedingly soft and conformable and whereof the outer portion is of such nature as to afford the requisite insurance against soiling of garments; and to provide in strip form material possessed of the characteristics recited for eventual severance at will into diapers of any desired length.

With such and other objects in view, the nature, characteristic features, and scope of the invention will more readily be understood from the following detailed description taken in connection with the accompanying drawings wherein

Figure 1 is a perspective view of strip diaper material, the casing being parted and the filling opened to clearly disclose the nature of the components and their relationship.

Fig. 2 is a section on line 2—2 of Fig. 1.

According to my invention, I provide strip diaper material embodying essentially a filling and an envelope.

The filling is of duplex form and includes a primary or main absorbent pad 5, ranging medially and longitudinally of the strip and floated with relation to the other components so as to be conformable or adaptable. Element 5 is superimposed upon a secondary pad or mat 6, which extends well beyond its side limits and is fixed with relation to the strip. Evidently the filling elements 5 and 6 may be constituted of like or of dissimilar materials possessed of requisite absorbent properties. Preferably each is constructed of paper of spider web consistency, highly absorbent, and readily dis-

integrable. Element 5 is illustrated as composed of a number of sheets or laminæ 55 having an edge fold 7, and element 6 is illustrated as composed of soft-textured disintegrable layers 8 free of relative positive connection.

The casing or envelope comprises a cloth strip 9 and a paper strip 10, with their side margins relatively lapped, as at 11, and secured by lines of stitching 12, which also serve to anchor the pad element 6. The facing strip 9 may be any suitable porous or open mesh fabric of comparatively low cost material, for example gauze. However, ordinary gauze of commerce is relatively rough and exercises something akin to abrasive action. Hence, I prefer to employ filmated 70 gauze, an invention of Robert W. Johnson. This is surgical gauze filmated, without positive connection, with absorbent cotton or equivalent material in a free fibrous state. Gauze modified in this way is remarkably 75 soft textured, conformable and absorbent and yet is possessed of its characteristic mechanical action. The facing strip shown represents filmated gauze, the fiber 13 being next the filling.

The facing strip 10 is paper, treated in any usual way to make it fluid repellant, and it operates successfully to preclude discharge beyond the diaper, the longitudinal marginal tie performing a useful office in 85 this regard.

The strip diaper is of appropriate fixed width while its length is a matter of choice or requisition. It may be packaged in roll form, say in lengths of several yards, and may be sold either in package form or by the yard. The strip form is convenient for the attendant, requiring but a single cutting operation to provide an article ready for use.

Having described my invention, I claim:

1. Strip diaper material comprising a casing and filling, the casing embodying complementary facing elements whereof one is of soft textured open mesh fabric and 100 whereof the other is fluid repellant paper, the facing elements being marginally joined longitudinally of the strip.

2. Strip diaper material comprising a soft fluffy paper filling and appropriate 105 casing elements having their longitudinal

edges lapped and joined, the filling comprising superimposed elements whereof one is floated medially and longitudinally of the strip and whereof the other is secured to the 5 casing elements.

3. Strip diaper material comprising a filling including distinct absorbent mats whereof one is fixed and whereof the other is relatively movable for conforming purposes, and casing elements to which the 10

first mat is fixed along its longitudinal edges, one of said casing elements consisting of impervious material and the other casing element consisting of gauze having its under face modified to increase its absorbent capacity and to impart cushion attributes. 15

In testimony whereof I affix my signature.

DONALD G. MACKENZIE.
